UNITED STATES PATENT OFFICE.

GINO CARBONI AND CARLO TIRONI, OF FLORENCE, ITALY.

SYSTEM FOR PROTECTING TRAINS.

1,054,277.

Specification of Letters Patent. Patented Feb. 25, 1913.

Application filed January 12, 1910. Serial No. 537,711.

To all whom it may concern:

Be it known that we, GINO CARBONI and CARLO TIRONI, subjects of the King of Italy, and both residing at Florence, in the Kingdom of Italy, have invented certain new and useful Improvements in Systems for Protecting Trains, of which the following is a specification.

This invention relates to a system for preventing collisions between trains approaching each other from opposite directions, or between two trains where one train overtakes another.

The invention has for one of its objects to improve and simplify the construction and installation of systems of this character so as to be comparatively simple and inexpensive, and reliable and efficient in use.

Another object of the invention is to provide a simple and novel arrangement of sectional conductors along the railroad track whereby trains moving along the track in the opposite or in the same direction will be automatically stopped when they are in dangerous proximity, there being electrical means on each train as well as a source of current whereby each train will control the operation of the other. For instance, when two trains approach each other from opposite directions and arrive at a certain distance apart, both trains will be stopped in time to prevent a collision, while in the case of a rear train overtaking one ahead, the rear train will be automatically controlled and stopped by the train ahead, without the latter stopping, and this control of the rear train will remain until the forward train has reached a safe distance.

With these and other objects in view, as will appear as the description proceeds, the invention comprise the various novel features of construction and arrangement of parts which will be more fully described hereinafter and set forth with particularity in the claim appended hereto.

In the accompanying drawings, which illustrate one embodiment of the invention, Figure 1 is a diagrammatic view of the system showing two trains traveling in the same direction on the same track, and the forward train controlling the rear one. Fig. 2 is a diagrammatic view showing the operation of the system in case of two trains approaching each other from opposite directions.

Similar reference characters are employed

to designate corresponding parts throughout the views.

Referring to the drawings, 1 and 2 designate the track rails which may be suitably bonded to enable the rails to act as electric conductors for the circuits of the system. Extending longitudinally of the track and arranged in any suitable manner are sectional conductors designated generally by A, A', A''. Each conductor consists of two sections 3 and 4 which are offset with respect to each other and are connected together by cross-over connections 5. The sections 3 of all the sectional conductors are arranged to form a line a, b, while the sections 4 are arranged to form a line c, d. With respect to trains moving from the left to the right, the sections 3 are the entrance portions of the sectional conductors, while the sections 4 are the exit portions, but this relation is reversed with regard to trains moving from the right to the left. Between the inner and outer end of contiguous corresponding sections 3 and sections 4 are gaps 6 and 7, respectively, and the gaps 6 are staggered or offset with respect to the gaps 7. Consequently, the sectional conductor A is insulated from or electrically disconnected from the adjacent sectional conductor A', and this is true with regard to all the sectional conductors. At the outer extremity of each entrance section, such as 3, of the sectional conductors, is a gap-bridging extension or terminal 8, so arranged that the gaps 6 are bridged. Specifically, the gap-bridging extension 8 of the sectional conductor A' overlaps the inner portion of the section 3 of the sectional conductor A.

The outer extremities of the exit sections 4 are provided with gap-bridging extensions or terminals 9 that bridge the gaps 7. These gap-bridging terminals 9 extend in the opposite direction from the gap-bridging terminals 8. By means of these gap-bridging terminals, it is impossible for a train to ever occupy a position where its electrical devices will not be in electrical contact with two sectional conductors.

On each train are trolleys 10 and 11 which are insulated from each other and are adapted to run on the lines formed by the sections 3 and 4 of the sectional conductors. The trolley 10 is connected by a wire 12 with a source of current such as a dynamo 13 on the train, the opposite terminal of the

dynamo being connected by a wire 14 to the track rails 1 and 2, so that the latter form return conductors. The trolley 11 is connected by a wire 15 with suitable electrical means for controlling an air brake valve or other equivalent train-stopping means or signal (not shown), such electrical means being in the present instance an electro-magnet 16 which is connected in any suitable manner, as for instance by the wire 14, with the track rails 1 and 2.

In Fig. 1, trains T^2 and T' are represented as traveling from the left to the right, and in this case the train T^2 will be controlled and arrested by the forward train T' . Current flows in the path indicated by the arrows from the generator 13 of train T' , through the wire 12, trolley 10, gap-bridging terminal 9 of the sectional conductor A, through the parts 4, 5 and 3 of the latter, trolley 11 of train T^2 , wire 15, electro-magnet 16, wire 14, track rail 2, wire 14 of train T' , thus making a complete circuit and causing the train-stopping means of train T^2 to be actuated by the electro-magnet 16. Current can not flow from the generator 13 of train T^2 to the electro-magnet 16 of train T' , because the trolley 10 of train A has no electrical connection with the trolley 11 of train 1. When two trains approach each other within dangerous proximity, both trains are arrested, as will be understood by reference to Fig. 2. Current flows from the generator 13 of train T' , through the wire 12 to the sectional conductor A^2 , and through the latter to the trolley 11 of train T^2 , wire 15, electro-magnet 16, wire 14, generator 13 of train T' , wire 12, and trolley of train T^2 , section 4 of conductor A', trolley 11 of train T' , wire and electro-magnet 16 thereof, wire 14, and generator 13 of train T' . In other words, the electro-magnets of both trains will be energized to operate the brake mech-

anisms thereof. It will thus be seen that the same system will operate to prevent head-on or tail-end collisions. 45

Having thus described the invention, we claim,

In a system for protecting trains, the combination of a track, a plurality of sectional 50 conductors insulated from each other and from the rails of the track and each comprising an entrance and an exit section, and a cross-over connection uniting the sections, the entrance sections being arranged in a line and the exit sections being also arranged in a line, there being gaps between adjacent sections in each line, and a gap-bridging extension or terminal connected with the outer end of each section and overlapping the inner portions of adjacent sections, the gap-bridging extensions of one line of sections extending in the opposite direction from those of the other line of sections, with a train equipment having a 55 contact means for engaging each line of sections and the bridging extensions thereof, a source of current connected with one of the said contact means, means for connecting the source with the track rails, and 60 train-stopping means connected also with the track rails and with the other of said contact means adapted to be energized by current furnished by another train. 65

In testimony whereof we have signed our 70 names to this specification in the presence of two subscribing witnesses.
